DESIGN FOR A CLOTHESRACK

Milton D. Mendle, Clayton, Mo., assignor to American Fixture & Showcase Manufacturing Company, St. Louis, Mo., a corporation of Missouri

Application January 17, 1938, Serial No. 74,355

Term of patent 3½ years

To all whom it may concern:

Be it known that I, Milton D. Mendle, a citizen of the United States, residing at Clayton, St. Louis County, State of Missouri, have invented a new, original, and ornamental Design for a Clothesrack, of which the following is a specification, reference being made to the accompanying drawing, forming a part thereof, in which the figure is a perspective view of a clothesrack embodying my new design.

The dominant feature of the design is shown in full lines.

I claim—

The ornamental design for a clothesrack substantially as shown, and described.

MILTON D. MENDLE.
